UNITED STATES PATENT OFFICE.

KARL J. BERGGREN, OF SPOKANE, WASHINGTON.

SLEEPING-BED STRUCTURE.

1,132,906.

Specification of Letters Patent. Patented Mar. 23, 1915.

Application filed April 27, 1914. Serial No. 834,722.

To all whom it may concern:

Be it known that I, KARL J. BERGGREN, a citizen of the United States, residing at Spokane, in the county of Spokane and State of Washington, have invented certain new and useful Improvements in Sleeping-Bed Structures, of which the following is a specification.

This invention relates to improvements in out of door sleeping structures of that character wherein a bed structure is provided which is shiftable from in door to out door positions and vice versa.

It is one of the objects of the invention to provide the opening in the building wall through which the bed is projected into different positions, with inner and outer marginal jambs, and to provide the bed with a head and foot equipped with jambs for engagement with the jambs of the wall opening in such a manner as to close the latter against ingress from the exterior, in either of the positions which the bed may occupy.

It is a further object of the invention to provide means accessible to the occupant of the bed for shifting the latter from one position to another without necessitating additional help and without requiring the occupant to get out of the bed. In this connection, it is a feature of the invention to mount the bed upon running gear and to provide operating means mounted upon the bed and operatively connected with the running gear for shifting the bed.

Other objects and features of the invention will be more fully described in connection with the accompanying drawings and will be more particularly pointed out in and by the appended claims.

In the drawings:—Figure 1 is a sectional view taken through a portion of a side wall of a building and illustrating the application of one form of my invention. Fig. 2 is a sectional view on line 2—2 of Fig. 1. Fig. 3 is a sectional view on line 3—3 of Fig. 1. Fig. 4 is a detail detached view of a portion of the operating means. Fig. 5 is a sectional view on an enlarged scale through a portion of the foot board and showing the same folded. Fig. 6 is a similar view showing the structure in an open or unfolded position. Fig. 7 is a sectional view on line 7—7 of Fig. 5.

Like characters of reference designate similar parts throughout the different figures of the drawings.

In the form illustrated, 1 designates an exterior or side wall of a building or residence to which my invention is applied and a floor is shown at 2. The side wall 1 is 60 provided with an opening 3, which is shown as extending upwardly from the floor 1, or at a point adjacent thereto, and which is proportioned to permit passage of a bed therethrough into an out of doors position. 65 A run-way, which may be in the form of a platform 4, is shown projecting exteriorly from the wall 1, and the upper face of the platform is disposed in flush relation with the floor 2. The platform or run-way 4 may 70 be supported in any desired manner and may be provided with a railing or balustrade, but these are structural features which I do not deem it necessary to detail in the explanation of my invention.

I have illustrated a bed which includes side boards 5 and 6 which are connected with head and foot boards, 7 and 8, respectively, to form a bed structure. I have shown the bed structure mounted upon running gear so as to provide a rolling or shiftable structure that may be projected into different positions as shown in full and dotted lines. I prefer to provide the structure with front and rear axles 9 and 10 on 80 which I dispose front and rear wheels 11 and 12, respectively. The front axle 9 may be mounted in any suitable form of bearings 13, and like bearings 14 may be provided for the rear wheels 12. As regards the 85 front axle 9, I prefer to rigidly secure the wheels 11 thereto and I provide the front axle 9 with a sprocket wheel 15. On the side board 5 I mount a bearing bracket 16 having its ends secured to the side board 5, 90 as indicated at 17. In the bracket 16 and a suitable bearing 18, the latter being in the side board 5, I mount an operating shaft 19. Rigidly secured to the operating shaft 19 is a sprocket wheel 20, over which and the 100 sprocket wheel 15, is trained a sprocket chain 21 whereby oscillation of the operating shaft will impart rotation to the axle 9 in a direction dependent upon the direction of movement imparted to the operating shaft 19.

The operating shaft 19 is provided with a toothed or ratchet wheel 22, rigidly mounted thereon, and which is adapted to be rotated by a device which is shown in the form of a 110 double pawl 23. An operating lever 24 is rotatively mounted on shaft 19 and is pro-

- vided with a pin supporting section 25 which is likewise rotatable on shaft 19, lever 24 and section 25 being terminally hubbed, as indicated at 26 and 27, for this purpose.
- 5 A pin 28 is rotatively mounted in lever 24 and section 25, or it may be fixed therein, and said pin supports pawl 23 in operative proximity to the peripheral teeth of the ratchet wheel 22.
- 10 I provide means for shifting the double pawl to dispose either end thereof in operative engagement with the ratchet 22 and to permit such end to slide idly over the ratchet teeth on return strokes of the lever 24.
- 15 As shown, I provide the pawl 23 with a spring retainer stem 29, which latter is provided with a locking pin 30. The lever 24 is provided with extensions 31 projecting laterally from the handle 32 thereof and 20 each extension is provided with a recess or socket 33 into which the locking pin 30 may be sprung, the pin being held in engagement therewith by the resiliency of the spring stem 29. I also provide the lever 24 with a 25 centrally disposed socket or recess 34 into which the locking pin 30 may be inserted when it is desired to adjust the pawl 23 to a neutral position.
- In the adjustment shown movement of 30 the lever 24 in the direction of the arrow shown in Fig. 1 will serve to rotate the shaft 19 and the sprocket wheel 20 in the same direction, which will be a contra-clockwise direction, a like direction of movement being 35 imparted to axle 9 so as to shift the bed in the direction of the arrow from the full line to the dotted line position. It will now be understood that a reverse adjustment of the pawl 23 would serve to rotate the shaft 19 in 40 a clockwise direction so as to shift the bed into an out of doors position. It will be seen that it is not necessary for the occupant to get out of bed in order to shift the latter from one position to another, and I consider 45 this an important feature of my invention since it is the object of my invention to give the user or occupant of the bed the benefit of out door air without necessitating any dangerous exposure of his person in shifting the 50 bed from one position to another.
- It is also a very important object of this invention to close the opening 3 when the bed is either in an in door or out door position so that the employment of my invention 55 will not interfere with maintenance of an even interior temperature. In the most preferred construction I equip the bed with head and foot boards which are proportioned and shaped to close the opening 3 60 and I extend said boards downwardly toward the floor in such close relation thereto as to provide a mere working clearance so that either head or foot boards may substantially completely close the opening 3 when 65 the bed is in either of its extreme positions.

First referring to the head board structure 7, the same is provided on its upper and side marginal edges with inwardly facing step jambs 35 and 36 and the inner margin of the opening 3 is provided with complementally formed step jambs 37 for engagement with the jambs 35 and 36, it being understood that the jambs 37 extend along the top and downwardly along the sides of the opening 3. Thus when the bed is shifted to an out 75 of doors position as shown in dotted lines in Fig. 1, the abutting jambs will serve to close the opening 3. The opening 3 is provided with inwardly facing jambs 38 for engagement by novel form of foot board which I 80 will now describe in detail.

The foot board proper, as designated at 8, is reduced in height with respect to the head board in the usual and conventional proportion and therefore I provide the foot board 85 with an extensible section which is adapted to be extended to engage the upper jamb margin 38 of the opening 3, it being understood that the sides of the foot board 8 are shaped and proportioned to engage the outwardly 90 facing jamb 38 extending downwardly along the sides of the opening 3. The abutting jambs function to arrest outward movement of the bed on the platform 4.

Referring more particularly to the extensible section, as indicated at 39, the same is shown hinged to the foot board 8, as indicated at 40. The hinge 40 is so disposed and the foot board 8 and extension 39 are so proportioned that when the latter is adjusted into an extended position it will lie flush with the front and back faces of the foot board 8, thereby affording a continuous engagement between the foot board 8 and the extension 39 with the vertical jamb portions 38 throughout the height thereof. The extension 39 is shown provided with an inwardly facing upward jamb 40' and a side jamb 41, as indicated in dotted lines.

I provide an improved form of locking means for holding the extension either in a folded or extended position firmly against movement from such position, which means I will now describe in detail.

My improved lock is in the form of a rail 115 42 which is provided with an ornamental cross section of a form adapted to ornament the top ridge of the foot board when in a position shown in Figs. 1 and 5. The rail lock 42 has a sliding hinge connection so as to permit of its adjustment into the position shown in Fig. 5 to lock the extension 39 in a folded position, or into the position shown in Fig. 6, to lock the extension 39 in an unfolded or extended position.

As shown, I rigidly secure to the rail lock 42 one element 43 of a sliding hinge means and said element is provided with trunnions 44 which project into guideways or slots 45, formed in the remaining element 46, of said 130

hinge means. The element 46 is of trough or U-shaped cross section and the slots 45 are in the side walls thereof. The slotted element 46 is shown secured in a mortise 5 formed in the foot board 8 by means such as screws 47 and the hinge element 46 is shown extending substantially throughout the thickness of the foot board 8, and flush with the top thereof.

10 When the rail lock is in the position shown in Fig. 5, the extension 39, upon any tendency to move to the left of said figure, would engage the rail lock and would be prevented from any movement in such direction. If it were desired to unfold the extension, it would merely be necessary to 15 slidably shift the lock to the right of Fig. 5 until the trunnions 44 reach the right hand ends of the slots 45 whereupon the lock may 20 be swung into the position shown in Fig. 6 so as to permit the extension 39 to be folded into an upright position.

It will be noted by reference to Fig. 5 that the hinge means connecting the rail 25 lock with the foot board has its axis disposed at one side of the axis of hinge 40 which latter connects the extension 39 with the foot board 8. Likewise in Fig. 6, the axis of the hinge connection between the 30 rail lock and the foot board is at one side of the line of juncture of the extension 39 with the foot board. By reason of this arrangement, the rail lock automatically functions to lock the extension 39 in folded or 35 extended positions immediately upon adjustment of the parts. Furthermore, when the bed is in an in door position and the extension 39 is raised to the position shown in Fig. 1 in dotted lines, the rail lock will act 40 as a cleat to form a weather closure at the meeting juncture between the bottom of the extension 39 and the top of foot board 8.

It is believed that the advantages and 45 utility of my invention will be fully understood from the foregoing description and while I have herein shown and described one

specific form of my invention, I do not wish to be limited thereto except for such limitations as the claims may import.

I claim:—

1. In combination, a building including a floor and an exterior wall with an opening in the latter extending upwardly from the floor and affording communication between the interior of the building and the outer 55 air, a runway projecting exteriorly from said wall, a bed structure movable through said opening on said floor and runway into in-door or out-door positions and having a foot board, and an extension hinged to the 60 inner side of said foot board and adapted to be swung into an extended position to engage the margins of said opening and limit movement of said bed structure in one direction, said foot board and extension being 65 proportioned to close said opening when the latter is extended or swung into a projecting position, substantially as described.

2. In combination, a building including a 70 floor and a wall with an opening in the latter extending upwardly from the floor, a bed structure movable through said opening into laterally opposite positions with respect to said wall and said structure having a relatively high head portion proportioned to close said opening when the bed structure is shifted into one position with respect to said wall, said bed structure having a foot portion of reduced height with respect to said head portion, and an extension 75 mounted on said foot portion for projection therefrom to form with said foot portion a closure for said opening when said bed structure is shifted into a position opposite to said first named position, substantially as described.

In testimony whereof I affix my signature in presence of two witnesses.

KARL J. BERGGREN.
